UNITED STATES PATENT OFFICE.

WILLIAM A. PRINGLE, OF NIAGARA FALLS, NEW YORK, ASSIGNOR TO AMERICAN SALES BOOK COMPANY, LIMITED, OF TORONTO, ONTARIO, CANADA, A CORPORATION OF ONTARIO.

FEEDING DEVICE FOR COMPUTING MACHINES.

Application filed March 14, 1923. Serial No. 625,051.

This invention relates to an improvement in printing machines, and with respect to its more specific features to feeding mechanisms for such machines.

5 An object of this invention is to provide a new and improved means for supplying a duplicate record strip to writing position upon a platen from a single roll.

10 A further object is to provide new and improved means for use with a platen, by which a single web may be fed to a machine and folded longitudinally as it is fed.

15 A further object is to provide an arrangement whereby a strip having transfer material upon a portion of one face thereof may be so arranged as it is fed to a machine as to bring the said transfer material in position to make a manifolding record upon another portion of the strip.

20 Other objects will be in part obvious and in part pointed out hereinafter.

The invention accordingly consists in the features of construction, combinations of elements and arrangement of parts which 25 will be exemplified in the construction hereinafter set forth, and the scope of the application of which will be indicated in the following claims.

30 The invention is adapted to supply a multiple layer strip for manifolding purposes and in its specific embodiment, to supply a double layer strip to adding machines, typewriters, or the like. It is therefore specifically illustrated in that connection.

35 In the accompanying drawing forming a part of this specification wherein similar reference characters refer to similar parts throughout the several views,

40 Figure 1 is a side elevation of a printing machine, provided with the improved feeding mechanism,

Fig. 2 is a front elevation,

Fig. 3 is a plan view of a portion of the strip,

45 Fig. 4 is a plan view of the strip folding mechanism,

Fig. 5 is a side elevation of the same,

50 Fig. 6 is a side view showing the improvement applied to the printing machine of the typewriter class, a part only of the machine being shown,

Fig. 7 is a rear view of the same.

The embodiment of the invention shown in Figs. 1 to 5 inclusive, is a printing machine of the adding machine type, the said machine being indicated generally at 1. It has the usual setting keys 50, which properly arrange the type bars for printing, and they are operated to print by means of a lever 3 which is pivotally mounted, to swing longitudinally of the machine. The frame is composed of laterally spaced side plates 2, which are connected by shafts 4, 4^a and 5, the latter shaft 5 supporting the platen cylinder indicated at 6, and having the usual 55 knobs 7 for manipulating the cylinder. The shaft 4^a is stationary and supports the folding mechanism to be described, and the shaft 4 supports the reel which carries the paper strip.

70 The strip of paper indicated at 8, has half of one face coated with a suitable transfer material, indicated at 9, and between the transfer material and the plain portion of the strip a line of partial separation 10 is 75 provided, for facilitating the folding of the strip, and for facilitating the separation of the portions after they have been printed. The line of partial separation also prevents crumpling and bunching of the folded edge 80 of the strip while it is passing around the platen, and said line provides a crease upon which the fold may be easily made. The strip is supported by a suitable reel indicated at 11, and it is so supported that when the 85 plain portion of the strip is folded beneath the transfer faced portion, the said transfer face will be between the strips, so that when matter is impressed upon the upper face of the folded strip, there will be a duplicate on 90 the lower fold or plain portion of the strip. A suitable tensioning device is provided for the reel, the said device having also the function of guiding the strip and holding it in position on the reel. In the present instance 95 the device comprises a plate 12 having its ends bent laterally to form flanges as shown at 13, and one of the flanges is provided with an extension 14, having an angular portion 15 which laps upon one of the plates 2, and is pivoted thereto as indicated at 16. The body 12 of the plate rests upon the strip upon the reel, as shown in Fig. 1, with the flanges 13 depending at the ends of the reel,

and the plate not only tensions the strip on the reel, but also prevents lateral shifting of the coils of the strip.

The folding mechanism which is supported by the shaft 4 comprises a plate 17 of trapezoidal shape, and having secured thereto an angle plate 18, which carries a bearing 19 engaging the shaft 3. A set screw 20 is threaded through the bearing and engages the shaft, to hold the bearing in adjusted position. By loosening the bearing, the angle of the plate 17 with respect to the horizontal may be varied to insure the best results as the paper passes over the plate. The plate 17 supports a guide 21 for the folder, the said guide 21 having overlying flanges 22 and 23 at its opposite side edges. The flanges are spaced apart far enough to receive the full width of the strip, and they engage over the opposite side edges thereof, as the paper passes over the plate 21. The folding plate 17 has one folding edge 22' substantially at right angles to and on one side of the center line of the strip and another folding edge 23' making an acute angle with and lying on the other side of the center line. Preferably the latter edge 23' lies under the half of the strip carrying the transfer material and the former edge 22' lies under the other half. As shown the edge 22' is at right angles and the strip 23' at an angle of about 30°. A folding finger 24 is supported by the shaft 4^a and the said finger extends into a position to engage the plain face of that portion of the strip which carries the transfer material and to fold the same beneath the other portion of the strip, as the other portion is drawn sharply across the edge, thus bringing the transfer material which, after folding, is upon the upper face of the lowermost portion of the strip, into contact with the lower face of the uppermost portion of the strip, the fold being on the line of partial separation, as shown in Figs. 4 and 5. Referring to Figs. 2, 4, and 5, it will be noticed that the folding finger 24 is connected to the end of the shaft 4^a, outside the plate 2, and that it extends inwardly and forwardly to and beyond the central line of the strip, at which point it is provided with a gentle curve, for engaging the paper to smoothly turn under the same. The folded strip passes over a guard 25 and beneath the platen roll, being held against the roll at the front of the roll by a holding roller 26 which is journaled in supporting arms 27 on the frame. From the supporting roller 26, the strip passes upwardly adjacent to the printing mechanism, which impresses the matter to be printed thereon.

The operation of the device is as follows:

The reel being provided with a strip of paper of the character described, the end of the strip is passed over the plate 21, with the edges of the strip beneath the guides 22

and 23. That edge of the strip not provided with transfer material is folded beneath the other edge after which the folded strip is drawn over the guard and beneath the platen roll. When now the platen roll is operated to feed the paper, by the lever 3, which is shown as connected to operating mechanism for the platen roll by a link 28, the strip will be drawn through the folding mechanism, which will operate to fold, the folding being controlled by the feeding of the paper.

In Figs. 6 and 7, the feeding mechanism is shown in connection with the carriage 29 of a typewriter indicated at 30 of any usual or desired construction. The carriage has the usual platen roll 31, which is operated to feed the strip of paper indicated at 32 by the carriage shifting lever shown at 33, or by the knobs 34 on the ends of the roll. The carriage is laterally translatable, as is usual,

and the movement of translation in one direction is brought about by the operation of printing. In the opposite direction the movement of translation is brought about manually. The strip of paper is fed from a reel 35, corresponding to the reel 11 of Fig. 1. The reel is journaled in a frame 36 supported at the rear of the carriage 29, and the folder indicated at 37 which is the same as that shown in Figs. 4 and 5, is supported by a rod 38 forming a part of the frame 36. The strip 32 of paper is of the same character as that shown in Fig. 3, and as it is fed by the platen roll, the strip is folded upon itself so that when printed upon, there will be an original and a duplicate copy.

The printing mechanism not shown, cooperates with the platen roll. A tensioning device 40 is provided for tensioning the strip, the said device cooperating with the paper on the reel, and corresponding to that shown at 12 in Fig. 1. The machine in either instance prints a duplicate, and after the print is completed, the duplicate may be separated from the original if desired. The strip is placed on the reel with the face having the transfer material inward and adjacent to the guide 23. As the strip passes through the folder, the face having the transfer material

is turned beneath the plain portion, but as the strip passes beneath the platen roller, and moves in front of the same, the plain portion is at the rear, that is adjacent to the platen roll.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is in-

tended to cover all of the generic and specific features of the invention herein described, and all statements of the scope of the invention, which, as a matter of language, might 5 be said to fall therebetween.

Having described my invention, what I claim as new and desire to secure by Letters Patent is:

1. A device of the character described, 10 comprising in combination, a roll platen, a support for a paper strip adapted to support a strip with its elements parallel to the elements of the platen, means for feeding said strip over said platen, and means between 15 said strip and said platen for folding a portion of the strip in manifolding relation to another portion.

2. A device of the character described, 20 comprising in combination, a roll platen, a support for a paper strip adapted to support a strip with its elements parallel to the elements of the platen, means for feeding said strip over said platen, and means between 25 said strip and said platen for folding said strip longitudinally to superpose one lateral portion of the strip upon another as it lies upon the platen for manifolding purposes.

3. A device of the character described, 30 comprising in combination, a platen, a support for a paper strip, means for feeding said strip over said platen, means between said strip and said platen for folding said strip longitudinally to superpose one lateral 35 portion of the strip upon another as it lies upon the platen for manifolding purposes, including a guide having folded edges presenting different angles to different lateral portions of the strip, and means for controlling, laterally, the position of the strip upon the guide.

4. A device of the character described, 45 comprising, in combination, a platen, a support for a supply strip, means for feeding paper from said supply into position for inscription on said platen including means to fold the strip longitudinally to bring a portion of the strip beneath another portion to form a plurality of layers on said platen, 50 including a guide having a folding edge substantially normal to the center line of the strip and a second folding edge making a sharp angle with the center line.

5. A device of the character described, 55 comprising, in combination, a platen, a support for a supply strip, means for feeding paper from said supply into position for inscription on said platen including means to fold the strip longitudinally to bring a portion of the strip beneath another portion to form a plurality of layers on said platen, 60 including a guide having a folding edge substantially normal to the center line of the strip and a second folding edge making a sharp angle with the center line, and a fold-

ing finger adapted to engage the portion passing over the latter edge to fold it beneath the other portion.

6. A device of the character described, 75 comprising, in combination, a frame, a support for a paper strip supply carried by said frame, a folding guide carried by said frame in position to receive paper from said supply, said guide having a plurality of folding edges to engage different lateral portions of the strip and presenting different angles to the center line of the strip, to fold said strip and means for supporting said frame in position to feed said folded strip to a printing platen. 80

7. A device of the character described, 85 comprising, in combination, a frame, a support for paper strip supply carried by said frame, a folding guide carried by said frame in position to receive paper from said supply, said guide having a plurality of folding edges to engage different lateral portions of the strip and presenting different angles to the center line of the strip, to fold said strip, and means for supporting said frame 90 in position to feed said folded strip to a printing platen, and means for tensioning the web upon the guide. 95

8. A device of the character described, 100 comprising, in combination, a frame, a support for a paper strip supply carried by said frame, a folding guide carried by said frame in position to receive paper from said supply, said guide having a plurality of folding edges to engage different lateral portions of the strip and presenting different angles to the center line of the strip, to fold said strip, a folding finger for folding a portion of the strip around the one edge beneath the other portion of the strip, and means for supporting said frame in position to feed said folded strip to a printing platen, and means for tensioning the web upon the guide. 105

9. A device of the character described, 110 comprising, in combination, means for carrying a strip of paper, means for folding said paper to bring one portion thereof beneath another portion, a platen having its elements parallel to the elements of the unfolded strip, and means for feeding the folded strip into position upon said platen. 115

10. A device of the character described, 120 comprising, in combination, a support for a roll of paper, means for receiving paper from the roll and folding it longitudinally upon itself into a plane parallel to the axis of the roll.

11. A device of the character described, 125 comprising, in combination, a platen, a support for a strip adapted for use with a strip of paper divided longitudinally into a plurality of portions, transfer material on one face of one of said portions, means for folding said strip to bring said transfer material in contact with a plain surface of an- 130

other of said portions and means for feeding said folded strip into position for inscription on said platen.

12. A device of the character described, comprising, in combination, a platen, a support for a supply strip and means for folding said strip of paper longitudinally including a guide for the strip having a folding edge at right angles to the strip beneath one portion of said strip and a folding edge at an angle to the strip beneath the remaining portion of the strip, means for bending one half of said strip sharply about said first mentioned folding edge and a finger for guiding the other half of said strip about said second mentioned folding edge to bring it beneath said first mentioned half in position for inscription on said platen and means for tensioning the strip.
13. A device of the character described, comprising, in combination, a support for a supply strip and means for folding a strip of paper longitudinally including a guide for the strip having a folding edge at right angles to the strip beneath one portion of said strip and a folding edge at an angle to the strip beneath the remaining portion of the strip, means for bending one-half of said strip sharply about said first mentioned folding edge, and a finger for guiding the other half of the strip about the second mentioned folding edge to bring it beneath said first mentioned half, and means for tensioning the strip, and means for adjusting the angularity with which said strip is folded about said first mentioned folding edge.
14. A device of the character described adapted for use with a strip having transfer material upon one lateral half of one surface thereof, comprising in combination, a support for the strip, a folding guide, a folding edge on said guide at an acute angle to the center line of the strip on the side to underlie said transfer material and a second folding edge substantially at right

angles to said center line to engage the other half of the strip, means to draw said strip sharply across said second edge and a finger to fold the half of the strip bearing the transfer material, around said first edge. 50

15. A device of the character described, comprising, in combination, a support for a paper strip and means for folding said strip longitudinally to bring a portion of the strip beneath another portion to form a plurality of layers, including a guide having a folding edge presenting substantially normal to the center line of the strip and a second folding edge making a sharp angle with the center line. 55

16. A device of the character described, comprising, in combination, a support for a paper strip and means for folding said strip longitudinally to bring a portion of the strip beneath another portion to form a plurality of layers, including a guide having a folding edge presenting substantially normal to the center line of the strip and a second folding edge making a sharp angle with the center line, and a folding finger 70 adapted to engage the portion passing over the latter edge to fold it beneath the other portion.

17. A device of the character described, comprising, in combination, a support for a supply strip, means for folding said strip longitudinally, including a guide for the strip having a folding edge at right angles to the strip beneath one portion of the strip and a folding edge at an angle to the strip beneath the remaining portion of the strip, means for bending one-half of said strip downwardly about said first mentioned folding edge and a finger for guiding the other half of the strip around the second mentioned folding edge to bring it beneath the first half, and means for tensioning the strip. 75

In testimony whereof I affix my signature.

WILLIAM A. PRINGLE.
